INTERNAL COMBUSTION ENGINE

Filed May 14, 1923

INVENTOR
Walter F. Vose
By *Jeff & Jeff*
ATTY'S.

UNITED STATES PATENT OFFICE.

WALTER F. VOSE, OF BLOOMINGTON, ILLINOIS.

INTERNAL-COMBUSTION ENGINE.

Application filed May 14, 1923. Serial No. 638,781.

To all whom it may concern:

Be it known that I, WALTER F. VOSE, a citizen of the United States of America, residing at Bloomington, in the county of 5 McLean and State of Illinois, have invented certain new and useful Improvements in Internal-Combustion Engines, of which the following is a specification.

My invention relates to internal combustion engines.

The object of my invention is in the improvement of the so-called four cycle type of internal combustion engine whereby a more perfect oil seal between piston and 15 cylinder walls result.

Another object of my invention is in the particular structure and arrangement of the combustion chamber whereby a more efficient burning of the fuel may be effected.

20 A further object is in the provision of an oil seal mechanism having in connection therewith means for by-passing any unused fuel or lubricating particles for the purpose of re-vaporization.

25 Other objects of my invention will appear in the following specification, in connection with the annexed drawings, in which:—

The single figure of the drawing is a vertical sectional view of a single cylinder of 30 the conventional four cycle internal combustion engine of L head type.

For the purpose of illustration, I have included only the necessary structural features of a conventional internal combustion engine, or rather, those features necessary in 35 the illustration of my improvements thereon.

In other words, the base portion of the engine, consisting of the crank case, crank shaft, bearings and valve operating mechanism has not been shown, inasmuch as these 40 portions are merely formal in engine design.

In the drawings is shown an exceptionally elongated cylinder 10 adapted to be connected to a formal crank case, not shown. This cylinder 10, is conventional in design, except for its exaggerated length, and is surrounded by the formal cooling means or water jacket 11, cast integrally therewith.

50 I have shown my invention as applied to a single cylinder engine, but the application may be extended to any number of cylinders and to any type of motor.

Slidably within the cylinder 10 is the 55 piston 12, having a head portion 13, and a cylindrical collar 14 extending upwardly

substantially the length of the cylinder wall thereabove. At 15 is shown a formal connecting rod having connection with the crank shaft, not shown. A cylindrical sleeve 60 16, flanged at its upper end as at 17 to engage receptive portions 18 in the upper ends of the cylinder, and lying flush therewith, extends downwardly in such manner as to form an inner wall for the cylindrical 65 collar 14.

In the figure the piston is shown in its extreme upward position, or rather on the compression stroke. The chamber thereabove, has inserted therein a cylindrical 70 aluminum block 19, having a passageway 20 therethru, connecting the valve members 21 with the small combustion chamber 22. This passageway thus forms a part of the explosion chamber, inasmuch as the gases 75 are fired thru-out its length, as well as above the valves and in the small chamber directly above the piston. The aluminum block 19 is shaped at an intermediate part of the passageway to form a slight venturi 23. A 80 single intake valve of the poppet type has been shown and is of conventional form except that due to the elongation of the cylinder wall the stem 24 thereof, must also be lengthened. A second exhaust valve, not 85 shown, lies directly beyond the intake valve and is also of formal design and operated as does the intake valve by the conventional cam means, not shown. The intake, or valve throat, is shown at 25 and has connection 90 with the formal carburetor manifold, not shown.

A removable head 26 is bolted to the cylinder block at 26^a and to the aluminum block at 27. This removable head portion is of 95 formal design and has screwed therein a spark plug 28 co-operating with the formal electrical circuit. Above the piston collar, there appears a small air space 29 and a by-pass is shown at 30 connecting said space 100 with the intake or valve throat 25.

I have confined my showing merely to the portions of a conventional internal combustion engine which constitute my improvements and have not thought it necessary to 105 go into an elongated description of the structure and operation of this conventional engine, in view of its universal use.

The only changes in the formal design of the engine itself is in the elongation of 110 the cylindrical block and valve members, the other portions being absolutely the same,

However, the upper end of the cylinder wall has been fashioned to receive the cylindrical sleeve 16 and also there has been a by-pass drilled between the intake port and air space 29.

In describing the operation of the present structure it may be said that the operation is similar exactly to that of any four cycle engine wherein the cycle of operation including intake, compression, explosion and exhaust takes place. In the present structure, the cylinder wall has been extended and there has been also an elongation of the piston. Again, to provide an inner wall for this extended piston, there has been inserted the sleeve 16. The above structure has been provided to prevent the escape of condensed fuel to the crank case chamber, not shown, and thereby the dilution of the cylinder oil therein. My present structure has been designed for as near perfect an oil seal as possible, between the piston and cylinder wall, whereby there will be maintained a more constant compression and thereby a more efficient operation of the engine under all conditions. My structure likewise prevents the products of combustion from coming in direct contact with the cylinder walls proper, inasmuch as the piston on its downward stroke does not go far enough to withdraw its extended collar portion from between the cylinder wall and sleeve 16.

For the purpose of providing a more efficient combustion chamber, which was necessarily enlarged by the extension of the cylinder wall and piston, the aluminum block, having the described peculiar design, was inserted therein. This aluminum block has its passageway restricted in the form of a venturi at a point intermediate its length for the following purpose:—On the intake stroke the fuel gases are drawn thru the valve throat, around the valve and into the combustion chamber. In view of the fact that the fuel gases now travel a somewhat longer distance than usual the aluminum block has been restricted intermediate its length to increase the speed thereof just before entering the chamber directly above the piston and approximately at a time when they are exploded. This restriction of the aluminum block prevents condensation of the gases thus permitting a more efficient operation of the engine.

Although my present structure is designed to prevent the passage of any condensed fuel to the crank case, however, there is a still further assurance of this in the following:— An air space is left directly above the extended piston and a by-pass is drilled to the intake throat. This air space would ordinarily have a slight vacuum on the down stroke of the piston and a slight pressure on the up stroke thereof. Now in case there

was gathered in this portion either oil coming up from the crank chamber or condensed fuel from the combustion chamber, this residue would be forced into the intake throat and burned up in the next successive engine operation. For the purpose of transmitting this possible residue from the air chamber 29 I have described the simple by-pass. However, my invention includes in a multiple cylinder engine, of taking this residue thru appropriate tubes, perhaps to a liquid trap or filter, and from this to the intake manifold.

What I claim is:—

1. In a four cycle internal combustion engine including valve and spark mechanism, an elongated cylinder member, cooling means therefor, a reciprocating piston in said cylinder having an extended collar portion, a flanged sleeve providing an inner wall for said collar and forming with the cylinder an air chamber above the extended collar portion, and means for by-passing any un-used fuel or lubricating particles in said chamber to be used in successive engine operations. 90

2. An internal combustion engine including valve and spark mechanism, an elongated cylinder member, a reciprocating piston in said cylinder having an extended collar portion, a flanged sleeve providing an inner wall for said collar, and means for by-passing un-used fuel and lubricating particles to be used in successive engine operations. 95

3. An internal combustion engine, including valve and spark mechanism, in combination, an elongated cylinder member, a reciprocating piston in said cylinder, having an extended collar portion, a filler block 105 providing an inner wall for the collar of the piston, as well as a means for restricting the size of the combustion chamber, and means for by-passing the unused fuel and lubricating particles to prevent their passage down the cylinder walls. 110

4. An internal combustion engine, including valve and spark mechanism, an elongated cylinder member, fashioned to provide a sleeve member, a reciprocating piston in said cylinder having an extended collar portion slideable in said sleeve and means for by-passing unused fuel and lubricating particles in a manner to be used in succeeding engine operations. 115

5. An internal combustion engine, including valve and spark mechanism, and elongated cylinder member, a block located in said cylinder member in a manner to restrict the combustion chamber therein, and to provide a flange portion, a reciprocating piston in said cylinder, having an extended collar portion slideable between the cylinder wall and flange member, and means for by-passing any unused fuel or lubricating par. 130

ties in a manner to be consumed in succeeding engine operations.

6. An internal combustion engine, including valve and spark mechanism, an elongated cylinder member, fashioned to provide a sleeve member, a reciprocating piston in said cylinder, having an extended collar portion slidable in said sleeve and means for maintaining a continual oil seal between the cylinder and piston including an air space above the piston and a connection with the valve members.

7. An internal combustion engine including valve and spark mechanism, an elong-

gated cylinder member, fashioned to provide a sleeve member, a reciprocating piston having an extended collar portion slideable in said sleeve and means for providing a continual oil seal between the piston and cylinder and at the same time by-passing the waste fuel and lubricating particles including a connection with the valve mechanism whereby the valve action maintains the oil seal as well as drawing off the waste particles from the combustion chamber, due to the suction action thereof.

In testimony whereof I affix my signature.

WALTER F. VOSE.
